METHOD OF PRODUCING SCORING
IMPLEMENTS

Carl Herzog, Montclair, N. J.

Application July 5, 1949, Serial No. 103,061

7 Claims. (Cl. 76—24)

1

My invention relates to a method of producing implements for scoring glass articles, such as ampules, and to the implements.

An important object of the invention is to provide a method whereby scoring elements of a given length may be formed from a continuous metal ribbon in an expeditious manner.

A further object of the invention is to coordinate the several steps of the method for producing the desired results.

A further object of the invention is to harden the serrated edge of the implement without hardening the major portion of its body so that the implement will not readily break.

In the accompanying drawings, forming a part of this application, and in which like numerals are employed to designate like parts throughout the same,

Figure 1 is a diagrammatic side elevation of apparatus employed in the practice of my method.

Figure 2 is a plan view of the ribbon roll and pull roll and associated elements.

Figure 3 is a fragmentary plan view, upon an enlarged scale of the supporting or ribbon drum of the cutting mechanism and the cutters,

Figure 4 is a transverse section taken on line 4—4 of Figure 3,

Figure 5 is a transverse section through the ribbon upon the completion of the cutting.

Figure 6 is a plan view of the knurl and associated roller, parts broken away.

Figure 7 is a further enlarged plan view of the ribbon and knurl, parts broken away.

Figure 8 is a transverse section taken on line 8—8 of Figure 6, parts broken away.

Figure 9 is a transverse section of the ribbon after the completion of the knurling.

Figure 10 is an enlarged transverse section taken through the ribbon upon the line 10—10 of Figure 1, associated elements being shown in elevation and broken away.

Figure 11 is a transverse section through the ribbon upon the completion of the grinding.

Figure 11a is a side elevation of a burner tip or nozzle, the associated ribbon being shown in section, and,

Figure 12 is a plan view of a completed product produced by the method.

In the production of the implements, I start with a spool or roll of metal ribbon 20 which is supported upon a horizontal shaft 21 to rotate in a vertical plane. This metal ribbon is formed of carbon steel. The ribbon 20 is passed over a supporting or ribbon roll 22 rigidly mounted upon a horizontal shaft 23, to rotate in a vertical plane.

2

The roll 22 turns in the direction of its arrow and preferably has a circumferential speed of about 40 feet per minute. The roll 22 is provided at one end with an annular flange 24, serving as an abutment for the ribbon 20. Arranged in advance of the ribbon roll 22 of the cutting mechanism is a grooved pull roll 25 rigidly mounted upon a horizontal shaft 26 to rotate in a vertical plane. The shaft 26 is driven by a shaft 26', through the medium of a slip clutch 27. The shaft 26' is rotated in a direction to turn the pull roll 25 in the direction of its arrow which is opposite to the direction of rotation of the ribbon roll 22. The shaft 26 has a greater circumferential speed than the ribbon roll 22. The pull roll 25 can pull the ribbon only as fast as it is fed by the ribbon roll 22, but due to the increased circumferential speed of the shaft 26 and the slip clutch, the pull roll 25 retains the ribbon taut between the pull roll 25 and the ribbon roll 22. The ribbon 20 is passed over the ribbon roll 22 and beneath the pull roll 25 and is pressed into engagement with the roll 25 so that it will not slip thereon by rollers 31, which are spring pressed.

One edge of the ribbon 20 engages the flange 24, while its opposite or free edge projects axially beyond the roll 22 and is engaged by spaced cutting tools 32. These cutting tools are suitably angularly arranged to form an inclined or beveled face 20' upon the ribbon 20. The cutting tools are spaced different radial distances from the ribbon roll 22 and each successive cutting tool is nearer to the roll 22 with respect to the leading end of the ribbon or the direction in which the roll 22 is turning. It is thus seen that as the ribbon travels over the roll 22, it is brought successively into engagement with the stationary spaced cutting tools which successively cut or plane the free end of the ribbon for providing the beveled face 20'. This beveled face is disposed uppermost. In order that the ribbon may not slip upon the roll 22, it is passed beneath flanged guide rollers 33, disposed upon opposite sides of the ribbon roll 22 at the elevation of its axis of rotation. The rolls 33 are driven in the direction of their arrows and have the same circumferential speed as the ribbon roll 22. The rolls 33 are spring pressed against the ribbon and are positively driven and may be geared to the roll 22. The ribbon is therefore held in firm engagement with the upper half of the periphery of the roll 22. It is thus seen that the ribbon is guided and fed longitudinally and during this feeding movement, its free longitudinal edge is successively

cut by the stationary cutting tools to provide the upper beveled face 20'.

After the cutting of the beveled face 20', the then tapered, beveled or sharpened free edge of the ribbon is subjected to a knurling operation, while the ribbon is still traveling over the ribbon roll 22 for forming teeth T. This knurling operation is effected by a knurl 34, disposed near the free end of the roll 22 remote from the flange 24. The knurl is rotatably supported to turn upon a vertical axis and is positively held in position. As the ribbon passes behind the knurl 34, the teeth 35 of the knurl form the teeth T. These teeth T are formed in that portion of the ribbon having the beveled face 20'. The teeth 35 are radially shorter than the width of the beveled face 20' and the teeth T have their spaces 36 terminating short of the inner edge 37 of the beveled face 20', as clearly shown in Figure 7. The teeth 35 are longer than the teeth T and the teeth T have straight edges 36' and sharp corners 37'. Due to the beveled face 20' and the knurling action a light burr 38 is formed upon the free edge of the ribbon or its teeth T. Figure 9 shows the ribbon in cross section after the cutting and knurling operation.

The next step in the method is to grind the serrated edge of the ribbon upon that side thereof remote from the beveled face 20'. The grinding is effected after the ribbon leaves the ribbon roll 22 and the ribbon is then passed beneath a roll 39, having a flange 40. The roll 39 has a horizontal axis of rotation. The roll 39 may be positively driven at the same circumferential speed as the roll 22 or it may be turned by contact with the ribbon. The ribbon also passes over grooved rollers 41, having horizontal axes of rotation. The ribbon is held taut and is retained in firm engagement with the roll 39. The serrated edge of the ribbon projects axially beyond the roll 39, and the serrated edge is subjected to the action of a rotary grinding wheel 42, having a horizontal axis 43 extending longitudinally of the ribbon and at a right angle to the axis of rotation of the roll 39. The grinding wheel 42 is driven by any suitable means. The grinding wheel 42 is arranged beneath the roll 39 and the grinding wheel is adjusted to bring the same into engagement with the lower face of the serrated edge of the ribbon, to effect the desired cut. The grinding wheel cuts a lower beveled face 44 upon the teeth of the ribbon and this lower beveled face intersects the upper beveled face 20', producing the sharp cutting edges 36', and removing the burrs. The metal ribbon thus treated is formed of carbon steel, which has not been hardened, and the next step in the method is to harden the teeth or beveled edge of the ribbon. This is effected by passing the ribbon through a heating unit 46, in which flames are projected upon the serrated edge of the ribbon from burners 46', Figure 11a. The flames from the burners heat the serrated edge of the ribbon, to a red or cherry red heat, throughout their entire thickness, but the remainder or body portion of the ribbon not engaged by the flame is not so heated. After the heat treatment of the serrated or cutting edge of the ribbon, the ribbon is immediately passed through a quench device 47 and the then heated cutting edge of the ribbon is chilled by contact with cool or cold water, in accordance with the usual method of hardening metal. The serrated or cutting edge of the ribbon is therefore hardened throughout its entire thickness while the body portion of the ribbon remains in its

normal condition and is not rendered brittle and will not break.

After passing from the quench 47, the teeth are subjected to the action of a scale removing grinding wheel or wheels 48, driven by any suitable means.

The ribbon 20 passes about and below the pull roll 25, as stated, and is provided above this pull roll with a loop 20a. The ribbon then passes to a reciprocatory feeding element 49 and through a check 50 before it reaches the reciprocatory feeding element 49 to prevent back feed. The reciprocatory feeding element 49 provides a step-by-step feed of the ribbon, for a selected length for each step, and the ribbon is then passed beneath a punch 51 which severs the ribbon into the implements of the desired length and forming curved and straight ends 52 and 53. Since a reciprocatory feeding element 49 is provided, it is difficult to properly time the same with respect to the continuous feeding ribbon and the loop 20a is provided for this purpose. The reciprocatory feeding element 49 will advance the ribbon slightly faster than the pull roll 25 and when the loop 20a is reduced to a given point, this loop swings a lever 52' forwardly, which lever has a part engaging the ribbon. The lever opens a switch which controls the drive of the reciprocatory feeding element 49. The reciprocatory feeding element is then stopped momentarily while the pull roll 25 continues to rotate and as soon as the proper loop 20a is restored, the lever being biased in that direction closes the switch and the reciprocatory feed element again starts.

The completed implement is shown in Figure 12. The implement includes a body portion which is not hardened having the fine sharpened teeth T which are hardened throughout their entire thickness. The entire inclined or beveled face 20' is thus hardened, as indicated by the shade line in Figure 12. The teeth T have sharp straight edges 53' corresponding to the edges 36' and sharp corners 54' corresponding to the corners 37'. This implement is useful in scoring ampules containing chemicals or medicines which must be completely sealed prior to their use. It is customary to score such ampules prior to breaking.

While I have shown apparatus suitable for the practice of the method, the practice of the method is not restricted to the use of this apparatus, as other types of apparatus or parts thereof may be used, and the method also may be practiced by hand.

It is to be understood that the form of my invention herewith shown and described is to be taken as a preferred example of the same and that certain changes may be resorted to in the order of the steps of the method, without departing from the spirit of my invention or the scope of the subjoined claims.

Having thus described my invention, I claim:

1. The method of producing scoring implements from a metal ribbon, comprising supporting and feeding the ribbon longitudinally, cutting one edge of the ribbon during its longitudinal travel for producing a beveled face, then knurling the edge of the ribbon having the beveled face during its longitudinal travel for forming teeth, then cutting the beveled edge of the ribbon upon the side thereof remote from the beveled face for cutting off the free ends of the teeth and providing the teeth with oppositely disposed beveled faces and sharp cutting edges, hardening the

teeth thus formed, and severing the ribbon to produce the implements.

2. The method of producing scoring implements from a metal ribbon, comprising supporting and feeding the ribbon continuously longitudinally, cutting one edge of the ribbon during its longitudinal travel for producing a beveled face, then knurling the edge of the ribbon having the beveled face during its longitudinal travel for forming teeth, then cutting the beveled edge of the ribbon upon the side thereof remote from the beveled face for cutting off the free ends of the teeth and forming the teeth with oppositely disposed beveled faces and sharp cutting edges, then hardening the teeth thus formed during the longitudinal travel of the ribbon, effecting an intermittent longitudinal movement of the ribbon at its leading end portion, and severing the leading end of the ribbon to produce the implements.

3. The method of producing scoring implements from a metal ribbon, comprising supporting and feeding the ribbon longitudinally continuously, cutting one edge of the ribbon during its longitudinal travel for producing a beveled face, then knurling the edge of the ribbon having the beveled face during its longitudinal travel for forming teeth, then cutting the beveled edge of the ribbon upon the side thereof remote from the beveled face for cutting off the free ends of the teeth and forming the teeth with oppositely disposed beveled faces and sharp cutting edges, hardening the teeth thus formed, effecting an intermittent longitudinal movement of the leading end of the ribbon and maintaining a loop in the ribbon, and severing the leading end of the ribbon in succession to produce the implements.

4. The method of producing scoring implements from a metal ribbon, comprising supporting and feeding the ribbon longitudinally, cutting one edge of the ribbon to produce a beveled face, knurling the edge of the ribbon having the beveled face for forming teeth, then cutting the beveled edge of the ribbon upon the side thereof remote from the beveled face for cutting off the free ends of the teeth and providing the teeth with oppositely disposed beveled faces and sharp cutting edges, hardening the teeth thus formed without hardening the body portion of the ribbon, and severing the leading end of the ribbon to produce the implements.

5. The method of producing scoring implements from a metal ribbon, comprising rigidly supporting a portion of the ribbon and feeding the same longitudinally, subjecting the free edge of the ribbon while rigidly supported and traveling

to planing actions for cutting a beveled face, then knurling the edge of the ribbon having the beveled face during the rigid supporting and longitudinal travel for forming teeth, rigidly supporting the ribbon after the knurling, then grinding the free edge of the ribbon upon the side thereof remote from the beveled face while it is traveling and rigidly supported for cutting off the free ends of the teeth and providing the teeth with oppositely disposed beveled faces, then hardening the teeth thus formed, and severing the leading end of the ribbon to produce the completed implements.

15 6. The method of producing scoring implements from a metal ribbon, comprising rigidly supporting a portion of the ribbon and feeding the same longitudinally, subjecting the free edge of the ribbon while rigidly supported and traveling to a planing action for cutting a beveled face, then knurling the edge of the ribbon having the beveled face during the rigid supporting and longitudinal travel for forming teeth, then grinding the free edge of the ribbon upon the side thereof remote from the beveled face during the rigid supporting and longitudinal travel for cutting off the free ends of the teeth and providing the teeth with oppositely disposed beveled faces and elongated sharp edges, then hardening the teeth thus formed without hardening the body portion of the ribbon, and then severing the leading end of the ribbon to produce the implements.

20 7. The method of producing a scoring implement from a metal ribbon, comprising supporting and feeding the ribbon longitudinally, cutting one edge of the ribbon to produce a beveled face, knurling the edge of the ribbon having the beveled face for forming teeth, forming sharp cutting edges upon the teeth, hardening the teeth thus produced, and severing the ribbon for producing the implement.
